FIG.5

FIG.6

FIG.7

FIG. 8

FIG. 1 is a side elevational view of a mixer for liquids or the like embodying my new design;

FIG. 2 is a front elevation thereof;

FIG. 3 is a rear elevation thereof;

FIG. 4 is a top plan view thereof;

FIG. 5 is a side elevational view of a modified form of the design shown in FIG. 1;

FIGS. 6 and 7 are front and rear elevations, respectively, of the modified form, and

FIG. 8 is a top plan view thereof.

I claim:

The ornamental design for a mixer for liquids or the like, substantially as shown and described.
